UNITED STATES PATENT OFFICE.

JOHN AULD, OF CHICAGO, ILLINOIS.

DESIGN FOR A COPY-HOLDER.

SPECIFICATION forming part of Design No. 37,193, dated October 25, 1904.

Application filed August 25, 1904. Serial No. 222,184. Term of patent 7 years.

To all whom it may concern:

Be it known that I, JOHN AULD, a subject of the King of England, residing at Chicago, in the county of Cook, State of Illinois, (and whose address is Room B, 205 La Salle street,) have invented a new, original, and ornamental Design for Copy-Holders, of which the following is a specification, reference being had to the accompanying drawings, forming part thereof.

Figure 1 in the drawings shows a front view of the copy-holder, and Fig. 2 shows a side view thereof.

I claim as new and desire to secure by Letters Patent—

The ornamental design of a copy-holder, as herein shown.

JOHN AULD.
